COMBINED PATIENT'S CHAIR AND CABINET UNIT

Robert C. Park and Jon K. Park, both of 911 Brown Bldg.,
Wichita, Kans. 67202

Filed Feb. 14, 1966, Ser. No. 1,021

Term of patent 14 years

(Cl. D15—3)

FIG. 1

FIG. 2

FIG. 3

FIG. 4

FIG. 1 is an upper rearward perspective view of a combined patient's chair and cabinet unit showing our new design;

FIG. 2 is a lower perspective view of the combined patient's chair and cabinet unit of our new design showing the underneath side thereof;

FIG. 3 is an enlarged fragmentary view of the head support section of the patient's chair and a full perspective view of the cabinet unit of our new design; and

FIG. 4 is an upper forward perspective view of the patient's chair and a fragmentary view of the cabinet unit showing our new design.

The dominant features of our design reside in those portions shown in full lines on the drawing.

We claim:

The ornamental design for a combined patient's chair and cabinet unit, substantially as shown and described.
